UNITED STATES PATENT OFFICE.

GEORGE SAYRE, OF ORLEANS, INDIANA.

TABLE.

1,394,222.

Specification of Letters Patent. Patented Oct. 18, 1921.

Application filed December 21, 1920. Serial No. 432,271.

To all whom it may concern:

Be it known that I, GEORGE SAYRE, a citizen of the United States, residing at Orleans, in the county of Orange, State of Indiana, have invented a new and useful Table; and I do hereby declare the following to be a full, clear, and exact description of the invention, such as will enable others skilled in the art to which it appertains to make and use the same.

The invention relates to tables and has for its object to provide a table comprising a frame to which frame is pivotally secured substantially centrally thereof, an oblong shaped top of substantially the same size as the frame and adapted to register therewith thereby forming a top for the table. Also to hingedly connect to one of the longitudinal edges of the cover, a leaf which 20 leaf when disposed in a horizontal plane and the pivoted cover moved to a transverse position engages the upper side of the table frame and is held in a horizontal plane, and to provide a removable leaf having cleats 25 thereunder for engaging within the end of the frame thereby forming an enlarged table top, said cleats forming means for preventing longitudinal movement of the removable leaf and for preventing upward movement 30 of the inner edge thereof.

With the above and other objects in view the invention resides in the combination and arrangement of parts as hereinafter set forth, shown in the drawings, described and 35 claimed it being understood that changes in the precise embodiment of the invention may be made within the scope of what is claimed without departing from the spirit of the invention.

40 In the drawings:—

Figure 1 of the table showing the pivoted cover longitudinally disposed and the hinged member in lowered position.

Fig. 2 is a transverse sectional view 45 through the table taken on line 2—2 of Fig. 1.

Fig. 3 is a top plan view of the table, showing in dotted lines the positions assumed by the pivoted cover, the hinged 50 member and the detachable leaf when the table top is enlarged.

Fig. 4 is a longitudinal vertical sectional view through the upper portion of the table showing the hinged portion in a horizontal 55 plane and the detachable leaf in a horizontal plane.

Fig. 5 is a perspective view of the detachable leaf.

Referring to the drawings, the numeral 1 designates a rectangular shaped frame 60 which is supported by legs 2. The frame 1 comprises the side rails 3 and the end rails 4. Secured between the side rails 3 substantially centrally of the frame 1 and spaced from the upper edges of the rails 3 65 is a transversely disposed bar 5, on which bar the downwardly extending portions 6 of the pivoted table top 7 rest. Extending through the bar 5 and through the portion 6 of the pivoted table top is a bolt 8 which 70 forms a pivotal point for the table top 7 when said table top is disposed longitudinally or transversely in relation to the table frame 1.

Hingedly connected to one of the longitudinal edges of the pivoted top 7 as at 8^a is a leaf 9, which leaf when the table top 7 is longitudinally disposed as shown in Fig. 3, hangs downwardly adjacent the side of the frame 1 and when the table top 7 is 80 transversely disposed as shown in dotted lines in Fig. 3 the leaf 9 is held in the same plane with the pivoted table top 7 by engaging the upper sides of the rails 3 and the end 4 of the table frame 1 thereby enlarging the table top. When the pivoted table top 7 is transversely disposed as shown in Fig. 3, it will be seen that it will be necessary to provide a detachable leaf 10 for one end of the table. The leaf 10, on its 90 under face is provided with cleats 11 spaced from each other and having their ends extending beyond the inner longitudinal edge for engaging under the longitudinal edge 13 of the pivoted table top 7 thereby preventing upward displacement of the detachable leaf 10. The detachable leaf 10 is prevented from longitudinal movement by the cleats 11, the outer sides 13 of which engage the inner edges of the corner braces 14 thereby preventing longitudinal movement of the detachable leaf 10.

When it is desired to reduce the size of the table top, the detachable leaf 10 is removed, then the pivoted top 7 which is of 105 substantially the same size as the rectangular shaped frame 1 is swung around until it registers with said frame, at which time the hinged leaf 9 is allowed to move downwardly and assume a vertical position adjacent the side of the frame 1.

From the above it will be seen that a table

is provided, which may be easily and quickly extended in size and easily and quickly reduced in size as desired.

The invention having been set forth what is claimed as new and useful is:—

A table comprising a rectangular shaped frame, a pivoted cover pivoted to said frame substantially centrally thereof, a hinged leaf hingedly connected to one of the edges 10 of the pivoted cover, said pivoted cover and hinged leaf when transversely disposed uncovering one end of the rectangular shaped frame, a detachable leaf for covering said uncovered end, the under face of said detachable leaf being provided with spaced 15 cleats having their outer ends extending beyond the inner edge of the detachable leaf

and underlying the pivoted cover, the rear ends of said cleats engaging the inner side of the rectangular frame for holding the detachable leaf against outward movement, stops carried by the frame and engaging the sides of the spaced cleats and preventing longitudinal movement of the detachable leaf, said cleats and stops providing means 25 for preventing pivotal action of the table top as a whole.

In testimony whereof I have signed my name to this specification in the presence of two subscribing witnesses.

GEORGE SAYRE.

Witnesses:

CECIL R. MOSS,
CLARENCE E. SKELTON.
